CLAIM

The ornamental design for an automobile stepping bar, as shown and described.

DESCRIPTION

FIG. 1 is a perspective view of an automobile stepping bar showing the new design;

FIG. 2 is a top plan view thereof;

FIG. 3 is a bottom plan view thereof;

FIG. 4 is a rear elevation view thereof;

FIG. 5 is a front elevation view thereof;

FIG. 6 is a left side view thereof; and,

FIG. 7 is a right side view thereof.

The portions of the automobile stepping bar shown in broken lines form no part of the claimed design.
